UNITED STATES PATENT OFFICE.

CLARKSON A. DISBROW, OF NEW YORK, N. Y., ASSIGNOR TO THE RAIL JOINT COMPANY, OF NEW YORK, N. Y., A CORPORATION OF NEW YORK.

HOLDER FOR INSULATING UNITS IN INSULATED RAIL JOINTS.

1,408,725.

Specification of Letters Patent.

Patented Mar. 7, 1922.

Application filed November 17, 1921. Serial No. 515,883.

To all whom it may concern:

Be it known that I, CLARKSON A. Disbrow, a citizen of the United States, residing at New York, in the county of New 5 York and State of New York, have invented certain new and useful Improvements in Holders for Insulating Units in Insulated Rail Joints, of which the following is a specification.

10 This invention relates to new and useful improvements in insulated rail-joints generally, although more particularly to a holder for confining the insulating fibre.

The principal object of this invention is to 15 provide a simple and economical means for confining and protecting the insulation whereby it cannot escape when subjected to the loads and pounds it receives incident to the trains passing thereover.

20 Another object is to provide a holder for the insulated bearing plate wherein the construction is such that a built-up unit may be readily manufactured and as such may be readily applied to joint-bars of commercial 25 form.

Another object is to provide a holder for the purpose set forth which will permit of variations in the lengths of the bearing plates employed, and in the lengths of the 30 spacing blocks between the bearing plates.

In the drawings:

Figure 1 is a side elevation of a rail-joint embodying one form of my invention.

Figure 2 is a cross-sectional view thereof. 35 Figure 3 is a vertical longitudinal sectional view taken through the complete holder and insulating units.

Figure 4 is a perspective view of the holder showing the bearing plates properly 40 assembled.

Figure 5 is a detail cross-sectional view showing a modified form of holder.

Figure 6 is a detail cross sectional view showing a holder equipped with a bearing 45 plate having a curved rail-engaging surface.

Figure 7 is a detail sectional view illustrating the improvement applied to both the head and base of a joint bar.

Like reference numerals designate corre- 50 sponding parts throughout the several views.

Primarily the invention comprises a holder applied to a face of the joint bar and secured in such a manner as to prevent lateral or longitudinal displacement thereof, said 55 holder affording means for supporting any

predetermined number of properly positioned insulating units, each of which units includes a metallic bearing plate having a direct bearing and supporting engagement with the under side of the rail head. This 60 form of construction lends itself readily to a rolled length of bar of uniform section throughout, so that another advantage of this type of insulation in connection with economy of manufacture is that the same 65 section of joint bar may be used for rails of different fishing heights, simply by varying the thickness of the bearing plates either in the head insulation or in the base insulation or in both.

It will be understood that the principle 70 of construction, embodied in the present invention is applicable to either the head or base of a joint bar or to both the head and base of a joint bar, though preferably and 75 usually employed as the active part of the head of the bar, as shown in the drawings, but it should be noted that when both head and base insulation of this type are used it forms a very simple insulated joint that 80 can be applied to the rails in track as easily and quickly as an ordinary standard joint. This is of decided advantage when installing a joint in busy track, and where very little time is allowed for the work.

In carrying forward this general feature 85 of the invention, it will be understood that the holder for the spaced insulating units may be of different forms of construction and secured to the joint bar in different 90 ways, but since the essential features of the invention are well exemplified by the figures of the drawings, the details of these drawings will now be referred to, merely by way of examples of the invention.

Referring to the examples shown in the 95 drawings, the rails are designated by the numerals 5—5 and the joint bars by the numerals 6—6. The holder for one or more of the insulated bearing plates (insulating 100 units) is designated by the numeral 7 and in the example shown is fixedly positioned on the upper surface of the joint bar and is provided with a longitudinal channel or seat 8 formed therein and forming resultant 105 walls 9—9. A plurality of metallic bearing plates 10 are positioned within the channel and each plate is seated in an insulating cup 11 formed of strips of fibre or the like, the bearing plates projecting above the walls 9. 110

The bearing plates are held against lateral movement by the walls 9-9. Spacing blocks 12, preferably of metal are positioned in the channel and are respectively disposed between the bearing plates, and are rigidly secured to said bar, preferably by welding. These spacing blocks fill the channel so that the outer surfaces of the blocks are substantially flush with the outer edges of the walls 9 formed by the channel.

The transverse ends of each bearing plate may be beveled as at 13-13 and the adjacent end of each block 12 beveled as at 14 to overlap the adjacent ends 13 of the bearing plates and thereby securely retain said plates against outward and longitudinal movements relative to the bar. The insulating cups 11 thus insulate the bearing plates from the bar and also from the spacing blocks. One or more bearing plates may be employed with each joint-bar and may be of any suitable length. Furthermore, the spacing blocks may vary in length so as to vary the distances between the bearing plates. It will thus be seen that the bearing plates are fixedly secured to the bar and that the bar is fixedly secured to the joint-bar.

In manufacturing these holders, a channel bar of considerable length is employed. A spacing block is positioned within the channel and at one end thereof. This block is then spot welded or otherwise fixedly secured to the bar. An insulating cup and a bearing plate are then positioned in the channel and against the inner end of the block. Another block is then positioned in the channel and held tightly against the opposite end of the bearing plate while said block is being spot welded or otherwise fixedly secured against outward and longitudinal movements relative to the bar, and by means of the walls 9 formed by the channel, the plate is held against lateral transverse movements relative to the bar. These operations are repeated until the entire bar has been traversed. The holder thus formed is then cut into lengths, which may be coextensive with the joint-bars to which they are to be applied, or may be in shorter lengths or in a number of short lengths each independently secured to the joint-bars.

In securing the assembled holder to a joint-bar the channel bar is preferably welded to the head of the joint-bar at spaced intervals only, as indicated by the numerals 15. Thus the channel bar would not, in its entirety, be integral with the joint-bar and consequently would not be subjected to the strains, its location with reference to the horizontal neutral axis, would otherwise demand. The maximum top chord stresses would be in the broad area of the joint bar head proper underneath the channel bar or holder.

It will be also seen that by means of my improved built-up holders for the insulated

bearing plates, not only a considerable saving in manufacturing is effected, but there is a saving in labor of installation of the joint in track since there will be fewer parts to assemble.

It has already been pointed out that the invention is susceptible of modification without departing from the spirit or scope thereof and one of these modifications is shown in Figure 5 wherein the channelled holder is shown as being of a double channelled formation, the upper channel providing for the seating of the insulating units, and the lower channel producing a cap-like construction permitting the holder to be fitted over the head of the joint bar. In this form of the invention the ends of the channel bar could be bent down over the ends of the joint bar to thereby prevent longitudinal movement of the channel bar, while the lateral flanges of the channel bar would prevent lateral displacement thereof.

A desirable embodiment of the invention is shown in Figure 7 of the drawings wherein the improvement is illustrated as applied to both the head and base of the joint bar. In that form of construction it will be noted that the holding bar or channel bar may be welded to the joint bar on the inside, and as shown this modification admits of making the joint bar reversible; at the same time one which is provided with track spike clearance.

Other modifications and adaptations of the invention may be utilized and it will also be understood that minor changes in the form, proportion and details of construction may be resorted to without departing from the invention as set forth in the appended claims.

What I claim is:

1. An insulated rail joint including the joint bar, a holding bar, means for rigidly securing the holding bar to the joint bar, and a metallic bearing plate rigidly secured on said holding bar and insulated therefrom.

2. A holder for insulated bearing plates comprising a bar adapted to be positioned on a joint-bar, and having a longitudinal channel in its face, and a metallic bearing plate rigidly secured in said channel and insulated from said bar.

3. A holder for insulated bearing plates comprising a bar adapted to be positioned on a joint-bar, and having a longitudinal channel in its face, a plurality of spaced metallic bearing plates located in said channel, spacing blocks located in said channel between said bearing plates, and insulating means between the plates and the bar and between the plates and the blocks.

4. A holder for insulated bearing plates comprising a bar adapted to be positioned on a joint-bar, and having a longitudinal channel in its face, a plurality of spaced metallic bearing plates located in said channel,

- spacing blocks located in said channel between said bearing plates, and insulating means between the plates and the bar and between the plates and the blocks, said spacing blocks cooperating with the bearing plates to retain the latter against outward movement.
5. A holder for insulated bearing plates comprising a bar adapted to be positioned on a joint-bar, and having a longitudinal channel in its face, a plurality of spaced metallic bearing plates located in said channel, spacing blocks located in said channel between said bearing plates, and insulating means between the plates and the bar and between the plates and the blocks, the ends of said blocks overlapping the adjacent ends of the plates to retain the latter against outward movement.
10. 6. A holder for insulated bearing plates comprising a bar having a longitudinal channel formed in its face, spaced bearing plates located in said channel and having beveled transverse ends, spacing blocks rigidly secured in said channel between said bearing blocks and having beveled transverse ends overlapping the transverse ends of said bearing plates, and means for insulating said bearing plates from the bar and from the spacing blocks.
15. 7. The combination with a joint-bar, of a holder for insulated bearing plates comprising a bar extending longitudinally of said joint-bar and fixed thereto, and a metallic bearing plate rigidly secured on said bar and insulated therefrom.
20. 8. The combination with a joint-bar, of a holder for insulated bearing plates comprising a bar extending longitudinally of said joint-bar and fixed thereto, said bar having a longitudinal channel in its upper face, and a metallic bearing plate rigidly secured in said channel and insulated from said bar.
25. 9. The combination with a joint-bar, of a holder for insulated bearing plates comprising a bar adapted to be positioned on a joint-bar, and having a longitudinal channel in its face, a plurality of spaced metallic bearing plates located in said channel, spacing blocks located in said channel between said bearing plates, and insulating means between the plates and the bar and between the plates and the blocks.
30. 10. A holding-bar for insulated rail-joints provided with a longitudinal channel, and a metallic bearing plate secured in said channel and insulated from said holding-bar.
35. 11. A holding-bar for insulated rail-joints provided with a longitudinal channel, a plurality of spaced metallic bearing plates located in said channel, spacing blocks located in said channel between said bearing plates, and insulating means between the plates and the bar and between the plates and the blocks.
40. 12. An insulating rail-joint including the joint-bar, a metal holder extending longitudinally of the bar, means for rigidly fastening the holder to the joint bar, and a plurality of spaced insulated metallic bearing plates carried by said holder and adapted to have direct engagement with the rail head.
45. 13. A holder for insulated bearing plates comprising an imperforate holding bar rigidly secured to the joint-bar, and a metallic bearing plate rigidly secured on said holding bar and insulated therefrom.
50. 14. An insulating rail-joint including the joint-bar, an imperforate metal holder extending longitudinally of the bar and rigidly secured thereto, and a plurality of spaced insulated metallic bearing plates secured to said holder and adapted to have direct engagement with the rail head.
55. In testimony whereof I hereunto affix my signature in the presence of two witnesses.
60. CLARKSON A. DISBROW.
